UNITED STATES PATENT OFFICE.

MICHAEL SWYRYD, OF WINNIPEG, MANITOBA, CANADA.

DESIGN FOR A WEAPON.

48,995.

Specification for Design.

Patented May 2, 1916.

Application filed February 19, 1916. Serial No. 79,459. Term of patent 7 years.

To all whom it may concern:

Be it known that I, MICHAEL SWYRYD, a subject of the Emperor of Austria-Hungary, residing at Winnipeg, Manitoba, Canada, have invented a new, original, and ornamental Design for a Weapon, of which the following is a specification, reference being had to the accompanying drawing, forming part thereof.

The figure is a view in side elevation of a weapon, showing my new design.

I claim:—

The ornamental design for a weapon, as shown.

MICHAEL SWYRYD.

Witnesses:

WILLIAM BORSA,
PETRO BORYE.
